UNITED STATES PATENT OFFICE.

ARTHUR DICKERSON, OF SALT LAKE CITY, UTAH.

IGNITION DEVICE.

1,267,991.

Specification of Letters Patent. Patented May 28, 1918.

Application filed June 28, 1916. Serial No. 106,535.

To all whom it may concern:

Be it known that I, ARTHUR DICKERSON, a citizen of the United States, residing at Salt Lake City, in the county of Salt Lake 5 and State of Utah, have invented certain new and useful Improvements in Ignition Devices, of which the following is a specification.

My invention relates to ignition devices 10 for internal combustion engines and has for its objects to provide an ignition device whereby a low tension electric circuit may be changed and the voltage increased and automatically distributed and timed to 15 cause the ignition of the compressed gases in the respective cylinders with less wiring, fewer parts and economy of space, cost of construction and intricacy of adjustment now in use, and particularly to provide a 20 compact device whereby one coil may be used with a source of current and the increased voltage distributed and timed to cause the ignition of the compressed gases in any number of the co-acting cylinders.

25 These objects I accomplish with the device illustrated in the accompanying drawings in which similar letters and numerals of reference indicate like parts throughout the several figures as described in the specification forming a part of this application and pointed out in the appended claims.

In drawings in which I have shown a substantial embodiment of my invention, Figure 35 1 is a diagrammatic view of a four cylinder internal combustion engine with my device in place thereon. Fig. 2 is an end elevation of the device looking toward the engine, parts shown in dotted lines. Fig. 3 is a section on line 3 3 of Fig. 2. Fig. 40 4 is an end elevation of the rotating member. Fig. 5 is a side elevation of the same. Fig. 6 is a side elevation of the device. Fig. 7 is a section on line 7 7 of Fig. 6. Fig. 8 is a section on line 8.8 of Fig. 6. Fig. 9 is a detail of the contact spring and 45 covering therefor.

In ignition systems heretofore used on a great many of the co-acting internal combustion engines where high tension magnos are not used and the space in which the ignition device can be placed is limited, the sparking device of the cylinder has been an individual high tension electric circuit, the current of which may have been 50 automatically distributed and timed, but by devices unlike that shown and described

herein. In the present invention the spark plug of each of the cylinders is in turn brought into one high tension electric circuit, the current of which is distributed and 55 timed by a novel device economical in construction, compact in form, needing no adjustment and the spark of which is intensified and prolonged.

In the drawings illustrating my device a 60 diagrammatic engine having four cylinders is shown as A. The source of electric energy shown is battery B. The coil C. The individual spark plugs 1, 2, 3, and 4, respectively. The timing shaft is shown at 65 D. The gear case for the gear wheels that connects the timing shaft with the engine shaft as E and my timing and distributing device as a whole as F. The device consists of a cup shaped cylindrical casing 70 75 5, which is made of insulating material, and is operatively held on the end of said gear case with its axis in alinement with the timing shaft of said engine. The fastening means shown consists of 80 an outwardly extended integral flange 6, which is closely fitted within an annular recess cut on the end of the gear case E, and which retains the said casing 5 from lateral displacement but allows slight rotation of said casing on its axis. A brace 85 arm 9 is secured on the breather pipe G of the engine with its end portion bearing against the outer end of said casing 5 to retain it in longitudinal position. A contact post 8 is screwed axially into the bottom of said casing 5 and an insulated wire 90 c is connected therewith which leads to the high tensional terminal of the coil C. Metal contact screws 10 are radially screwed in 95 the wall of said casing and spaced apart and electrically insulated from each other by the material in the wall of said casing 5. There is one provided for each cylinder of the machine, those shown being four in 100 number. Contact posts 11 are screwed through the bottom wall of said casing 5 and into the said contact screws 10, and on 105 each of which is secured a jam nut 12. A radially disposed lever post 13 is also screwed in the wall of said casing to which the rod for advancing or retarding the spark is pivoted. A recess 14 is cut in the wall of said casing 5, and a curved contact spring 15 is secured on the periphery of 110 said casing and the curved portion thereof extended into the interior of said casing.

A contact screw 16 is used to fasten said spring in place, and a jam nut 17 is carried thereon. A curved cover for the inwardly curved portion of said spring 15 is shown 5 at 30. On the end portion of the timing shaft D of the engine is secured a rotating member 18 made of insulating material and somewhat similar in form to said casing 5, but smaller in diameter and operated in 10 said casing. Radially disposed contact screws 19 are inserted through the wall of said rotating member 18 and bear against said shaft D at the inner ends and with their outer ends rounded and protruding 15 slightly beyond the periphery of said rotating member and rounded to give a slight spherical form to the protruding surface. A curved spring 20 is secured in the end of said rotating member with its outer end slightly rounded and protruding 20 beyond the periphery of said rotating member 18 and the curved portion of the spring is made to extend beyond the end wall of 25 said member. An insulated wire a connects one of said contact posts 11 with the spark plug 1 in one of said cylinders and other wires b, d and e each connect one of said contact posts 11 with another of said spark plugs. A wire f leads from one of the low tension terminals of the coil C to the contact post 16. The operation of my device 30 is as follows:

The device is secured on the end of an engine frame and timing shaft as hereinbefore explained with the said rotating member 18 and casing 5 concentrically placed one within the other. A low tension electric circuit is established through the battery B, the primary winding of the induction coil 35 C, wire f, curved spring 15, the individual contacting screw 18 when touching said spring 15, and the shaft and frame of the engine as the ground. When the circuit is established in the primary as described the 40 secondary of the induction coil is energized with a high tension voltage, and this high tension voltage is then distributed to the respective spark plugs as follows: from the coil C through the wire e to the contact post 45 8, curved spring 20 and one of the respective contact screws 10 when the member 18 is rotated and the outer end of the curved spring 20 is brought into contact with the contiguous contact screw, and through its 50 contact posts and the respective wires, a, b, d, and e, to the said spark plugs. The said contact screws 10 and springs 15 and 20 are so positioned in said casing 5 and rotating member 18 that when the timing 55 shaft B of the engine is operated a high tension circuit will be established through the respective spark plugs and cylinders whenever the outer end of the spring 20 is brought in contact with the contiguous 60 screw 10 and the inner portion of the curved 65 spring 15 will contact at the same instant with one of the contact screws 19 in said rotating member 18 and the current will be distributed and timed to fire the compressed gas in the respective cylinders of the engine. 70

Should the operator desire to advance or retard the spark, as for instance to retard it to prevent back firing of the engine, he will move the said casing 5 with its contact- 75 ing curved spring 15 by means of the lever post 13 and its connections, in the direction that the timing shaft D is rotated, in order that the spring may not reach the respective contact members as quickly as when the members are in their normal position relative to said rotating member. 80

Having thus described my invention I desire to secure by Letters Patent, and claim:—

1. An ignition device consisting of a cylindrical cup shaped casing, having an opening in its wall; an outwardly extended flange on the rim thereof; a primary curved contact spring operable through said opening; radially disposed contact screws in the wall of said casing having rounded ends protruding within the interior thereof; contact posts through the end wall of said casing and connected with said contact screws; a secondary contact screw axially secured in the bottom wall of said casing; an induction coil electrically connected with said last mentioned screw; a rotatable timing shaft; a source of electric energy grounded on said shaft; an insulating rotary member secured on the end of said shaft and concentrically operable within said casing; contact screws radially disposed in the wall of said rotary member and in electrical connection with said shaft and having rounded ends protruding beyond the periphery of said rotating member each adapted to contact with said curved spring when said shaft is rotated; and a curved spring radially secured on the end of said rotary member with one end portion bearing against said secondary contact screw and the other end protruding beyond the periphery of said rotating member adapted to touch the inner ends of said screws in the wall of said casing. 90

2. An ignition device consisting of an induction coil; a source of electric energy; an engine having cylinders and spark plugs 100 therein; a timing shaft and a gear case thereon; an insulating member on the end of said shaft and rotating therewith; radially disposed contact screws in the wall of said member with ends protruding beyond 105 its periphery; a curved spring radially secured on the end of said member; an insulating casing concentrically mounted over said rotating member and having an opening in its wall; a spring operable through 110

said opening adapted to touch the protruding ends of said contact screws when said shaft is rotated; contact screws in the wall of said casing having rounded ends entering the interior of said casing and adapted to touch the end of said curved spring when said rotating member is operated; means to form a low tension electric circuit when either of the said contact screws in said 10 rotating member touches said spring in said

casing; and means to form a high tension electric circuit including said low tension circuit when the curved spring on the end of said rotating member touches either of the contact screws in the wall of said casing. 15

In testimony whereof I have affixed my signature in presence of a witness.

ARTHUR DICKERSON.
